BOTTLE

James E. Plummer, Toledo, Ohio, assignor to Owens-
Illinois Glass Company, Toledo, Ohio, a corporation of Ohio

Filed July 31, 1963, Ser. No. 76,055

Term of patent 14 years

(Cl. D58—9)

FIG. 1

The side not shown is the same as the side shown.

The dominant features of my design reside in the portion shown in full lines.

I claim:

The ornamental design for a bottle, substantially as shown and described.
